(57) **CLAIM**

The ornamental design for a scrub bottom, as shown and described.

DESCRIPTION

FIG. 1 is a top-front perspective view of a scrub bottom showing my new design;

FIG. 2 is a front elevation view thereof;

FIG. 3 is a rear elevation view thereof;

FIG. 4 is a left side elevation view thereof, the right side being a mirror image thereto;

FIG. 5 is a top plan view thereof; and,

FIG. 6 is a bottom plan view thereof.

The stipple-shaded areas shown in the drawings represent a change in appearance.
